UNITED STATES PATENT OFFICE.

ALMYR L. NEWMAN, OF WARWICK, AND OSCAR R. MITCHELL, OF CRANSTON, RHODE ISLAND, ASSIGNEES, BY MESNE ASSIGNMENTS, TO A. L. NEWMAN COMPANY, OF CRANSTON, RHODE ISLAND, A CORPORATION OF RHODE ISLAND.

FLEXIBLE BRACELET.

Application filed November 6, 1928. Serial No. 673,059.

This invention relates to articles of jewelry and particularly to improvements in flexible bracelets of the so-called box-link type.

One object of the improvement is to provide an article of the type specified which may be constructed of relatively light sheet stock while being strong and durable in use and substantial in appearance.

Another object of the improvement is to provide a bracelet which, while being flexible to accommodate itself to the wrist of the wearer, will be proof against lateral displacement or mis-alinement of the links.

Another object of the improvement is to provide a bracelet of neater and more ornamental appearance without unsightly joints or connections between its parts.

Another object of the improvement is to render the device simple in construction and economical to manufacture by the usual stamping processes.

Further objects of the improvement are set forth in the following specification which describes a preferred embodiment of the invention as illustrated in the accompanying drawings. In the drawings:

Fig. 1 is a perspective view of a complete bracelet embodying one form of the invention;

Fig. 2, a magnified perspective view of one of the link-members of the bracelet;

Fig. 3, an enlarged bottom plan view of several of the connected links of the bracelet, showing two of said links in section on the line 3—3 of Fig. 2;

Fig. 4, an enlarged perspective view showing the shape of the sheet-metal blank from which the link is formed;

Fig. 5, a similar perspective view showing the blank partly formed; and

Fig. 6, a similar view of the completely formed blank shown with its bottom side up.

The present improvement is directed to a bracelet or other article of jewelry comprising a series of box-like link-members which are hinged or pivotally connected together to form a flexible chain. The link-members 2 are preferably struck up from sheet-metal in hollow box-like form and may be of rectangular shape, as shown in Fig. 2, and ornamented on their surface with engraving,

embossing, chasing or by piercing through the metal. In other cases the box-members or links may be set with imitation or precious stones or embellished in any other suitable manner.

Fig. 1 shows the complete bracelet with the links 2 thereof joined together in a chain, and usually a suitable clasp is provided for connecting the terminals of the chain. As the clasp may be of any usual construction it is not herein shown or described in detail. The links 2 of the bracelet are formed from sheet-metal blanks of the shape shown in detail in Fig. 4. As here illustrated, the blank 3 consists of a flat rectangular strip of metal 4 having integral lateral wings or tabs 5—5 extending from its longitudinal edges. The wings 5 have arcuate extensions 6—6 at either side, while their ends are formed with circular ears 7—7 which are pierced to provide holes 8—8 for the hinge-pins or pivots by means of which the links are connected together. The main strip 4 of the blank extends beyond the ends of the lateral wings 5 in a bifurcated tab-portion 9 adapted to be curled around in a loop to receive the pivot pin of an adjacent link. The wings 5—5, while integral with the main strip 4, are defined therefrom by a scored groove or crease 10 to adapt them to be bent up at right-angles to the main strip 4 to form the opposite parallel sides of the link. A groove or indentation 11 also defines the arcuate tabs 6 from the side wings 5 to provide for bending the tabs over to form the bottom of the link in the manner and for the purpose as later explained.

Referring now to Fig. 5, the wings 5 are bent upwardly from the main portion of the strip 4 to form the two sides of the link, as shown more particularly in Fig. 6. The end tab 9 is then bent upwardly and curled around in a loop 12 with its bifurcated end 13 extending horizontally between the sides 5—5 of the link. The arcuate extensions or tabs 6 are next bent down or folded along their scored grooves 11 so that they overlie the bifurcated portion 13 of the tab 9, as shown in Fig. 6 and also at the right in Fig. 3. The two legs of the bifurcated portion 13 of the tab 9 are thus held in place by

the side tabs 6 and the cut-out portion between the legs makes for a neater appearance on the bottom of the link.

It will be noted from Figs. 2 and 6 that the ears 7 project from the end of the sides 5 of the link in vertical relation to the main strip 4 which, as will be understood, forms the top of the link. At the opposite end of the link the loop portion 12 of the tab 9 operates with the ends of the sides 5 to provide a circular opening for the connecting hinge-pin for the links; it being noted that the edges of the sides 5 are cut away or recessed at 14 on a curve coinciding with that of the ears 7 at the opposite end of the link.

The manner of assembling the completed links to form the bracelet is as follows: The looped tab 12 at the end of one link is inserted between the projecting ears 7 at the end of the next adjacent link so that the holes 8 will come into alignment with the opening through the loop. A pin 15 is then inserted through the aligned holes and its ends riveted or swaged over on the outside of the ears 7. Preferably, the hinge-pin 15 for the links is made of tubular stock so that it may be constructed of relatively large diameter while yet being light in weight. This provides enlarged pivot bearings for the pin in the loops 12, thus making the bearing surfaces ample to resist wear. This construction also provides a stiffer, stronger connection between the links to guard against the parts becoming loose and shackly from wear.

It is to be noted that the curved edges of the ears 7 on one link are proportioned to fit snugly within the curved depressions 14 in the edges of the sides 5 of the next adjacent link in the series. That is to say, the ears 7 form the end bearings to take the thrust of the links toward each other, while the end thrust in the opposite direction, that is the stretching pull on the links, is taken by the pins 15 bearing within the looped portions 12 of the end tabs 9. Through this arrangement each link is caused to bear against its adjacent link at points on its opposite sides so that there can be no unwarranted play or loss-motion between the links when they are assembled in the bracelet. Stated briefly, one link braces the next against lateral play or twisting movement, and in this way all of the links are maintained in alignment and the whole structure rendered stronger and less liable to distortion.

It will be observed from the foregoing description that the present invention provides a particularly simple and neat construction for the mechanical elements of the bracelet, which not only makes for a more artistic and finished effect in the article but also renders it more substantial in appearance and durable in use. The links of the

bracelet may be manufactured most economically by striking them up from sheet-metal and forming them in suitable dies, and in connecting the links in the chain or bracelet no soldering is required so that the cost of manufacture is reduced to a minimum.

Various modifications may be made in the form and structure of the parts of the improved bracelet without departing from the spirit or scope of the invention; therefore, without limiting ourselves to the exact embodiment herein shown and described, we claim:

1. An article of jewelry comprising a series of box-like link-members each having a top and opposite parallel sides, the sides of the link being provided with curved ears pierced with openings, said ears made integral with and projecting from one end of the link and recesses at the opposite end of the link, to adapt the links to be assembled with the ears of one link received in the recesses of the next adjacent link, an integral tab formed into a loop at the recessed end of the link, and a pin inserted through the openings in the ears and through the loop to hingedly connect the links in the chain.

2. In a bracelet or like article of jewelry, the combination of a plurality of box-like link-members each having a relatively flat top and opposite parallel sides, circular ears formed integral with and projecting from the sides at one end of the link and pierced with holes, circular recesses in the sides at the opposite end of the link, a tab extending from the top of the link and curled around in a loop arranged substantially concentric with the recesses in the sides of the link, and a tubular hinge-pin inserted through the pierced holes in the ears of one link and through the loop at the end of the next link to join the links together in a flexible chain.

3. In an article of the type specified, the combination of a plurality of box-like link-members formed from sheet-metal blanks having a longitudinal top strip with side wings bent at right angles thereto, the ends of the sides being provided with circular ears pierced with openings and the top strip of the link extending in a tab bent into a loop with its end projecting between the sides of the link, and a pivot-pin inserted through the openings in the ears at the end of one link and through the loop at the end of an adjacent link to connect the links in a chain.

4. In an article of the type specified, the combination of a plurality of box-like link-members formed from sheet-metal blanks, said blanks having a relatively flat top strip with wings projecting from its sides and arcuate extensions projecting from the lateral edges of the wings, said wings bent at right angles to the top strip and the arcuate ex-

tensions folded at right-angles thereto in parallel relation with the top strip, said wings also formed with circular ears projecting at one end of the link and provided with holes, the opposite ends of the sides of the link being provided with curved edges adapted to register with the circular edges of the ears on an adjacent link, a tab extending from the top strip of the link 10 and curled around in a loop projecting from the end of the link with its extremity in

serted beneath the folded arcuate extensions on the sides of the link, and hinge-pins inserted through the ears at the end of one link and through the loop at the end of an adjacent link to connect the links together in a chain. 15

In testimony whereof we affix our signatures.

ALMYR L. NEWMAN.
OSCAR R. MITCHELL.
